(57) **CLAIM**

The ornamental design for a display screen or portion thereof with graphical user interface as shown and described.

DESCRIPTION

The sole FIGURE is a front view of a display screen or portion thereof with graphical user interface showing the claimed design.

The peripheral dashed broken lines illustrate a display screen or portion thereof, and form no part of the claimed design. The text illustrated in dashed broken lines forms no part of the claimed design. The remaining interior dashed

(Continued)

broken lines and portions within these lines illustrate portions of the graphical user interface that form no part of the claimed design.
